UNITED STATES PATENT OFFICE.

WILLIAM C. ANDERSON, OF TOLEDO, OHIO, ASSIGNOR TO THE AMERICAN CUT GLASS COMPANY, OF CHICAGO, ILLINOIS.

DESIGN FOR A GLASS DISH.

SPECIFICATION forming part of Design No. 27,062, dated May 18, 1897.

Application filed March 20, 1897. Serial No. 628,546. Term of patent 7 years.

To all whom it may concern:

Be it known that I, WILLIAM C. ANDERSON, of Toledo, county of Lucas, and State of Ohio, have invented a certain new and original Design for a Glass Dish; and I do hereby declare that the following is a full, clear, and exact description of the invention, which will enable others skilled in the art to which it appertains to make and use the same, reference being had to the accompanying drawings, and to the figures of reference marked thereon, which form part of this specification.

This design relates to a glass dish, and particularly to the ornamentation of the exterior surface thereof.

The drawings represent, in Figure 1, a bottom plan view of a dish containing the design, and in Fig. 2 a transverse section on lines *x* *x*, Fig. 1.

The leading features of my design are a bottom portion with a central prismatic stud surrounded by a ten-pointed star, with lines radiating from the star to the outer edge of the dish, each line being broken by circular concentric lines cut into the radial projections formed by the radial lines, with an interposed embellishment comprising conoidal lines or lines describing conoids, this effect being produced by intercepting conoidal lines, each of which alternates in coincidence with a point of the ten-pointed star, so that the apex of each conoid is in alignment with the point of a star, and the meeting points of the lines in immediate concentricity to the star also coincide with a point of the star, the lines forming positive and inverted conoids, the fields of which are embellished with a central rosette with pentagonal fields with checkering, the apex of each conoid divided by triangular

lines, the apex of each conoid having a transverse line for prismatic effect upon a field of checkering, with a transverse line and plain field in the point of the inverse conoid for refraction of light.

1 designates the central prismatic stud; 2, 45 the ten-pointed star; 3, the radial lines extending from the star to the edge of the dish, broken by circular concentric lines 4, cut transversely of the raised radial projections, forming refracting-prisms. The central body 50 of the dish is embellished with two alternating conoidal lines 5 and 6 or lines forming conoids 7, and by reason of the alternation (or rather crossing) of the conoidal lines forming inverted conoids 8, the apices 9 of the radial conoids coinciding with the points of the star and the points 10 of the inverted conoids also coinciding with the points of the star. The duplex conoids form a heptagonal field 11, with a central rosette 12 and a border 60 checkered by triangular lines forming prisms, with the apex 13 transversed by a line and a checkering above, and a like transverse line in the point 14 of the inverse conoid and a plain field. The prisms and pentagonal fields, 65 together with the radial lines and concentric lines, blend in producing a highly artistic and pleasing effect.

What I claim is—

The design for a glass dish herein shown 70 and described.

In testimony that I claim the foregoing as my own I hereby affix my signature in presence of two witnesses.

WILLIAM C. ANDERSON.
